Des. 213,127
Patented Jan. 7, 1969

213,127

LAMP POST
Peter A. Schork, Jr., 26136 Rose Road,
Westlake, Ohio 44091

Filed Oct. 31, 1967, Ser. No. 9,224

Term of patent 14 years

U.S. Cl. D48—31
Int. Cl. D26—03

FIG -1

FIG. 2

FIG. 3

FIG. 1 is a front view of a lamp post embodying my new design, with the side opposite to that shown being a mirror image thereof;

FIG. 2 is a top plan view of the base for the lamp post looking downwardly along the line 2—2 of FIG. 1;

FIG. 3 is a top plan view of the post for the lamp post looking downwardly along the line 3—3 of FIG. 1.

The lamp fixture in broken lines in FIG. 1 is shown for illustrative purposes only.

I claim:

The ornamental design for a lamp post, as shown and described.
